CLAIM

I claim the ornamental design for a fishing lure enhancement, as shown and described.

DESCRIPTION

FIG. 1 is a perspective view of a fishing lure enhancement, showing my new design;

FIG. 2 is a top plan view thereof;

FIG. 3 is a bottom plan view thereof;

FIG. 4 is a front elevational view thereof; and,

FIG. 5 is a rear elevational view thereof.

The broken lines showing a fishing lure in FIG. 1 depict environmental matter and form no part of the claimed design.
